United States Patent Office

Des. 209,895
Patented Jan. 9, 1968

209,895

SHAVER

Raymond A. Somers, Fairfield, and Raymond T. Cassidy,
Stratford, Conn., assignors to Sperry Rand Corpora-
tion, New York, N.Y., a corporation of Delaware

Filed June 8, 1967, Ser. No. 7,405

Term of patent 14 years

(Cl. D95—3)

Fig. 1.

Fig. 2.

Fig. 3.

Fig. 4.

Fig. 5.

Fig. 6.

FIG. 1 is a top view of a shaver showing our new design;

FIG. 2 is a front elevational view thereof;

FIG. 3 is a side elevation as seen from the right at FIG. 2;

FIG. 4 is a bottom view thereof;

FIG. 5 is rear elevational view thereof; and

FIG. 6 is a side elevation as seen from the left side of FIG. 2.

The essential features of the design reside in the portions shown in solid lines on the drawings.

We claim:

The ornamental design for a shaver, substantially as shown and described.
